United States Patent Office

Des. 188,920
Patented Sept. 27, 1960

188,920

PHOTOGRAPHIC PROJECTOR

Alan W. Duncan, Itasca, Ill., assignor to Sears, Roebuck
and Co., Chicago, Ill., a corporation of New York

Filed Sept. 16, 1959, Ser. No. 57,571

Term of patent 7 years

(Cl. D61—1)

FIG. 1

Des. 188,920

PAGE 2

FIG. 2.

FIG. 3.

FIG. 4.

Fig. 1 is a front perspective view of a photographic projector embodying my new design, with the film spool supports extended;

Fig. 2 is a back perspective view of the same;

Fig. 3 is a top plan view thereof, with the film spool supports retracted; and

Fig. 4 is a bottom plan view thereof.

I claim:

The ornamental design for a photographic projector, as shown.
